BATTERY CHARGING UNIT

Peter T. Quinn, Littleton, Colo., assignor to Honeywell
Inc., Minneapolis, Minn., a corporation of Delaware

Filed June 6, 1969, Ser. No. 17,555

Term of patent 14 years

Int. Cl. D13—02

U.S. Cl. D26—15

FIG. 1

FIG. 2

FIG. 3

FIG. 1 is a perspective view of the front and one side of a battery charging unit in accordance with the present invention;

FIG. 2 is a top view thereof; and

FIG. 3 is a bottom view thereof.

The back and remaining side of the unit are identical to the front and one side, respectively, shown in FIG. 1.

I claim:

The ornamental design for a battery charging unit, as shown and described.
